[57] **CLAIM**

The ornamental design of a wallpaper display unit, as shown
and described.

DESCRIPTION

FIG. 1 is a perspective view showing the front, left side, and
top of my wallpaper display unit; the right side is a mirror
image of the left side; the rear and the bottom are plain and
unornamented and are not a part of the claimed design;
FIG. 2 is a front view thereof; and,

FIG. 3 is a sectional view along line 3—3 of FIG. 2.
The broken line showing of displayed material is for illus-
trative purposes only and forms no part of the claimed
design.
